UNITED STATES PATENT OFFICE

LOUIS CASIMIR LONGCHAMP, OF EPINAY-SUR-SEINE, FRANCE

CLOSING DEVICE FOR TIN CANS AND THE LIKE

Application filed June 7, 1930, Serial No. 459,767, and in France June 13, 1929.

My invention relates to tin cans used for the packing of chemicals, cleaning and polishing preparations and the like. The tins most commonly used are those of which the lid 5 may be removed with the aid of a penny and which are provided with a collar projecting towards the middle of the box.

Now these tin boxes have amongst other inconveniences that of having an opening of small diameter, and a sharp projecting portion so that there is a certain difficulty and some danger in completely emptying the box. On the other hand when the tin is closed the lid is driven inside the box and consequently 15 a large portion of the interior is rendered useless. Lastly, when the tins are piled up there is no connection between them so that packing or exhibition in a show window is difficult.

20 Other kinds of tin cans having a nonprojecting collar are also utilized said collar being secured very close to the body of the can or in contact with same. This type of collar does not lend any rigidity to the top 25 of the body and consequently the slightest blow upon the packing crushes it, the lid falls out and the contents empties itself upon the other tins.

My invention has for its object a closing 30 system with collar and lid which obviates to said defects.

The collar of the container according to my invention presents a narrow horizontal flange 35 slightly lower than the upper edge of the container, then a relatively high vertical turned up wall which rises above the container, a vertical descending wall connected to the former by a rounded portion and lastly a turned-in upright rolled edge which 40 meets the upright wall of the collar and will bear upon it when the container is closed.

The lid has a convex bottom surface adjoining a conical portion followed by a cylindrical vertical wall of a diameter slightly 45 larger than that of the descending portion of the collar, said wall being connected through a rounded portion with a slightly descending wide horizontal flange ending in a small rolled edge.

50 When closing the tin, the inner rolled edge

of the collar and the convex bottom surface of the lid act as in the manner of a spring the conical part facilitating the introduction. The cylindrical portion of the lid is forced in that of the collar thus producing the necessary adherence to obtain a perfectly air tight closure. 55

On the other hand, the rounded part which connects the cylindrical wall of the lid with its horizontal edge which has the same radius as the one that connects the upright wall of the collar with its turned down wall engages the latter thus ensuring a perfectly air tight closure. The convex bottom surface of the lid gives an advantageous appearance 60 to the container the inner capacity of which is completely utilized. 65

The slightly turned down horizontal portion of the lid which is rigidified by its rolled edge provides a strong support for the opening. My invention comprises an opening lever provided with an inverted U-shaped head placed astride upon the container flange before the closing operation, in such a manner, that the inclination of the lever to the right or to the left raises the lid by the back of the U. 70

Lastly, the projecting portion of the container constituted by the collar and the lid has a diameter which allows its engagement 75 in the recessed portion of the container between its bottom surface and its lower flange, thus allowing the piled up cans to engage one upon the other and facilitating packing or exhibition in show windows. 80

The annexed drawings show by way of example a mode of execution of my invention.

Fig. 1 is a vertical sectional view of an open can with the lid off.

Fig. 2 is a vertical sectional view of a 90 closed can.

Fig. 3 is a front view of the key-lever used as opener.

Fig. 4 shows two superimposed cans.

Fig. 5 is a plan view, on a smaller scale of 95 a group of cans showing the position of the opener when packing.

As will be seen in the drawings the body *a* of the container is provided at its lower part with the usual inlaid bottom *b*. 100

A slightly set-in collar is secured in any suitable manner upon the upper part of the body *a*, in such a manner that its horizontal narrow portion *o* is on a lower level than the edge *a*¹ of the container. Next to the flat portion *e* the metal of the collar is pressed upwards so as to form a vertically rising wall *d* 6 to 7 millimeters high which is connected by a rounded portion *e* with a second vertical turned down wall *f*, an adjacent rolled edge *g* meeting the rising wall *d*.

Owing to its shape this collar has a great rigidity although its projecting part *c* is narrow thus providing a large opening for the container.

The lid is provided on the other hand with a convex bottom *h* next to the conical portion *i* ending in a vertical wall *j* having a diameter slightly larger than the inner diameter of the collar portion *f*. The wall *j* is connected through a rounded portion *k* having an inner diameter which is equal to the outer diameter of the rounded portion *e* and a horizontal turned down edge ending in a small rolled edge *m*. The upper surface of the convex bottom *h* may be on a lower level relatively to the plane tangent to the rounded portion *k* or even be flush with said plane.

It has already been seen that the conical part *i* facilitates the closing of the container, the bottom part *h* and the rolled edge *g* act in the manner of a spring when the part *j* is pressed in the cylinder *f* thus giving a good adherence, lastly the rounded portion *k* engages the rounded portion *e* ensuring an air-tight joint.

Before closing of the box a part *n* acting as a lever is placed in position and will serve to open it. The lever *n* is provided with a groove *n*¹ which is put astride upon the edge *a* and a turned-up edge *n*¹ upon or very near which the lid comes down. The lever *n* is provided with an edge *n*² in the shape of a lug which may be taken hold of for handling the box.

It will easily be seen that when said lever is moved either to the right or to the left the part *n*² will cause the lifting of the lid. Owing to its rolled edge the lid will be raised as a whole without being distorted.

The outer diameter of the lid is calculated so as to allow the latter to fit under the bottom surface *b* of a container placed underneath, thus allowing a certain engagement of the tins together when they are piled up.

It will also be seen in Fig. 5 that the key-levers *n* do not interfere in the grouping of the tins for packing purposes.

What I claim and desire to secure by Letters Patent of the United States is:

1. A tin can which comprises a cylindrical body or container, a lower bottom, a collar formed upon the upper part of said body which presents successively from the circumference towards the middle: a flat horizontal

portion slightly sunk-in relatively to the top of the container, a vertical cylindrical rising portion, a rounded portion, and a curled spring edge which bears upon the cylindrical rising portion, and a lid comprising: a convex bottom part, a conical portion rising from the periphery of said bottom, a cylindrical rising portion adjoining the former, the outer diameter of said cylindrical portion being slightly larger than the inner diameter of the cylindrical descending part of the aforesaid collar, a rounded portion having a radius equal to the outer radius of the rounded part which joins the two cylindrical portions of the aforesaid collar, a wide slightly descending flange and a small rolled edge upon the periphery of said flange.

2. A tin can comprising: a cylindrical container a lower bottom part for same, a collar formed upon the upper part of said container, said collar presenting successively from the periphery towards the middle: a flat horizontal narrow portion slightly sunk-in relatively to the top of the container, a cylindrical portion extending above same, a cylindrical descending portion and a curled spring edge bearing upon the rising cylindrical portion, and a lid which comprises: a convex bottom part, a low conical portion rising from the periphery of same, a rising cylindrical portion adjoining the former, the outer diameter of said cylindrical portion being slightly larger than the inner diameter of the cylindrical descending portion of the aforesaid collar, in such a manner that when the can is closed the rounded parts engage one upon the other, a wide slightly descending flange and a small rolled edge upon the periphery of said edge, the outer diameter of said rolled edge being smaller than the inner diameter of the lower bottom of the can body, in such a manner that two closed cans may partially engage one upon the other, and means to open said can.

3. A tin can comprising: a cylindrical container, a lower sunk-in bottom for same, a collar formed upon the top of the container, said collar presenting successively from the periphery towards the middle: a narrow flat horizontal portion slightly lower down than the top of the container, a cylindrical portion extending above same, a rounded portion, and a curled spring edge, the end portion of which is applied parallel against the cylindrical rising portion; a grooved lever placed astride upon the top of the container, a rising portion extending against the outer wall of the cylindrical part of the collar, and a manipulating lug; and a lid which comprises: a convex bottom part, a low conical portion rising from the periphery of same, a cylindrical rising portion adjoining the former, the outer diameter of said cylindrical portion being slightly larger than the inner diameter of the cylindrical descending

portion of the aforesaid collar, in such a manner that when the can is closed both parts are in engagement; a rounded portion having an inner radius equal to the outer radius 5 of the rounded portion which joins together both cylindrical portions of the aforesaid collar, in such a manner that when the can is closed both these rounded parts engage one upon the other; a wide slightly descending flange which when the can is closed comes above the rising portion of the aforesaid lever, and a small rolled edge upon the periphery of the descending edge of the lid, the outer diameter of said rolled edge 10 being smaller than the inner diameter of the lower bottom of the container, in such a manner that when two cans are closed they may partially fit one upon the other.

In testimony that I claim the foregoing 20 as my invention, I have signed my name.

LOUIS CASIMIR LONGCHAMP.
